UNITED STATES PATENT OFFICE

154,670

DESIGN FOR A COMPACT AND LIPSTICK
RECEPTACLEPaul Flato, New York, N. Y., assignor to Paul
Flato Sales Corp., New York, N. Y.

Application February 28, 1948, Serial No. 144,822

Term of patent 14 years

(Cl. D86—10)

To all whom it may concern:

Be it known that I, Paul Flato, a citizen of the United States of America, residing in New York city, county of New York, and State of New York, have invented a new, original and ornamental Design for a Compact and Lipstick Receptacle, of which the following is a specification, reference being had to the accompanying drawing, forming part thereof, wherein,

Figure 1 is a front elevational view of a compact and lipstick receptacle showing my new design.

Figure 2 is a side elevational view.

Figure 3 is a top plan view, and

Figure 4 is a bottom plan view.

I claim:

The ornamental design for a compact and lipstick receptacle, substantially as shown.

PAUL FLATO.
